(57) **CLAIM**

The ornamental design for a golf club face, as shown and described.

DESCRIPTION

FIG. 1 is a top perspective view of the golf club face herein; FIG. 2 is an enlarged view of a first embodiment of the golf club face shown in FIG. 1 within the boxed region; FIG. 3 is a cross-sectional view of the embodiment shown in FIG. 2 along lines 3-3; FIG. 4 is an enlarged view of a second embodiment of the golf club face shown in FIG. 1 within the boxed region; FIG. 5 is a cross-sectional view of the embodiment shown in FIG. 4 along lines 5-5;

FIG. 6 is an enlarged view of a third embodiment of the golf club face shown in FIG. 1 within the boxed region;

FIG. 7 is a cross-sectional view of the embodiment shown in FIG. 6 along lines 7-7;

FIG. 8 is an enlarged view of a fourth embodiment of the golf club face shown in FIG. 1 within the boxed region; and, FIG. 9 is a cross-sectional view of the embodiment shown in FIG. 8 along lines 9-9.

The broken lines showing other golf club features are included for the purpose of illustration only and form no part of the claimed design.

1 Claim, 5 Drawing Sheets
